UNITED STATES PATENT OFFICE.

WILLIAM A. SEAMAN, OF SAGINAW, MICHIGAN.

PUSH-ROD-OPERATING MECHANISM.

Application filed September 23, 1926. Serial No. 137,366.

This invention relates to improvements in push rod operating mechanisms for various kinds of machines, and has more particular reference to an automatic compensating or 5 self-adjusting tappet device particularly useful as an element of a valve operating mechanism for internal combustion engines and the like.

The conventional type of tappet, now in 10 common use in internal combustion engines, is manually adjustable, and is so adjusted as to leave a slight space or clearance between the tappet and the adjacent end of the valve stem or push rod operated thereby. This 15 space may be reduced through accurate adjustment of the parts so as to be substantially infinitesimal in measurement, but some space must be left to accommodate the expansion of parts due to the variation of temperature 20 in operation of the engine. The space necessarily existing between the tappet and the valve stem or push rod gives rise to objectionable tapping or hammering noises, due to sudden forcible contact of metallic parts during 25 the rapid reciprocation of the tappet. Further, the tappet, under the rapid lifting impulses of the operating cam, is driven against the valve stem or push rod with such force and so often as to cause objectionable 30 wearing of parts and undesirable vibration and stress throughout the valve mechanism, as well as causing, through wear, the clearance space to increase materially, thereby increasing the noise and causing other inefficiencies to arise.

The present invention has for its primary object the provision of a tappet which in operation, will constantly or continuously contact with the end of the valve stem or push 40 rod for thereby closing the clearance space which ordinarily must be left.

A further object is to provide a tappet of the above character which is extensible and compressible for automatically lengthening 45 and shortening to accommodate the variation in the length of the various parts of the valve mechanism caused by expansion and contraction from temperature changes.

Another object is to provide a tappet embodying a pair of telescopically and slidably associated members having an incompressible liquid cushion therebetween, means to supply the liquid of the cushion under pressure between said tappet members whereby the tap-

pet is lengthened for keeping the clearance 55 space closed and maintaining constant contact of the tappet with the cam and the push rod or stem, and means to partially relieve the liquid pressure of the cushion during the retreating movement of the cam whereby 60 the tappet is allowed to shorten for permitting complete return movement of the push rod and complete closing of the valve associated therewith.

A still further object is to relieve the liquid 65 pressure of the cushion by escape of the liquid from between the tappet members to a point between the contacting surfaces of the tappet and the cam, whereby when oil is employed as the liquid of the cushion, a film of oil will 70 be had between the surfaces for reducing wear, vibration and noise.

Still another object is to supply the liquid or oil of the cushion so that effective lubrication is had between the tappet and its guide 75 or slide bearing for further reducing wear and promoting the ease of movement of the tappet.

A further object is to provide a self-adjusting and shock absorbing tappet which employs a liquid cushion and which is entirely devoid of frail and objectionable metallic 80 springs and movable check valves.

Another object is to provide a tappet of the above character which is extremely simple 85 and durable in construction as well as efficient in operation.

Other objects will become apparent as the nature of the invention is better understood, and the same consists in the novel form, combination and arrangement of parts herein-after more fully described, shown in the accompanying drawings and claimed.

In the drawings, wherein like reference characters indicate corresponding parts 95 throughout the several views,

Figure 1 is a fragmentary elevational view, partly in section, illustrating a valve operating mechanism embodying the present invention;

Figure 2 is a horizontal section taken upon line 2—2 of Figure 1;

Figure 3 is a section taken on the line 3—3 of Figure 1;

Figure 4 is a horizontal section taken on 105 the line 4—4 of Figure 1;

Figure 5 is a vertical section taken substantially upon line 5—5 of Figure 1; and

Figure 6 is a fragmentary vertical sectional view illustrating a modification of a portion of the embodiment of the invention illustrated in Figures 1 to 5 inclusive.

Referring more in detail to the drawings, 5 indicates a conventional form of guide or slide bearing which is usually formed integral with the cylinder block of an internal combustion engine and which is provided 10 with a vertical cylindrical opening in which the tappet of the present invention is slidably fitted for vertical reciprocation. As is usual in constructions of this kind a rotatable cam shaft 6 is horizontally disposed below 15 and slightly spaced from the guide or slide bearing 5 and has a cam 7 fixed thereon in position to engage the adjacent lower end of the tappet mounted in the slide bearing 5 as shown clearly in Figures 1 and 5. The 20 adjacent lower end of the push rod or valve stem adapted to be engaged by the upper end of the tappet for being lifted to effect opening of the associated valve of the engine when the tappet is raised by the cam 7 is indicated at 8.

The present tappet includes a tappet body 9 which is centrally bored so that the upper end of the body is open and the bore is of cylindrical form, and so that the lower end 30 of the tappet body is provided with a bottom wall having an integral shoe or plate 10 adapted to ride on the edge or surface of the cam 7, the tappet body 9 being provided with a cylindrical outer bearing surface 35 adapted to snugly engage the bearing surface of the guide or slide bearing 5. The tappet further includes a tubular or cylindrical member or plunger 11 which is slidably fitted within the tappet body 9 and 40 adapted to project slightly above the upper end of the latter, the plunger or tubular member 11 including a cylindrical body which is centrally bored so as to be open at its upper end and closed at its lower end.

45 A valve lifting member is engaged in the tubular member or plunger 11, and as shown in Figures 1 to 5 inclusive, this valve lifting member may consist of a bolt 12 having its stem adjustably threaded in the upper end 50 of the plunger 11 so that its head is disposed to engage the lower end of the push rod or valve stem 8. As is well known in the art, the adjustment of the bolt 12 is maintained by means of a jamb nut 13 threaded upon 55 the stem of the bolt 12 and engaged against the upper end of the tappet, the nut 13 being engaged against the upper end of the tappet member or plunger 11 in the present instance.

60 The guide or slide bearing 5 is provided near its lower end with a transverse opening that communicates with the bearing opening of the guide 5 and has a nipple 14 threaded therein, which nipple is coupled as indicated at 15 with the adjacent end of 65 an oil pressure line 15 that may extend from

the outlet side of the oil pressure pump of the engine lubricating system. As shown clearly in Figure 5, the tappet body 9 is provided with an external annular groove 17 which is so located and of such relatively great width as to at all times communicate with the opening of the guide 5 in which the nipple 14 is secured, whereby the oil under pressure is constantly supplied to the groove 17 during the operation of the engine and 75 the reciprocation of the tappet. As is also clearly shown in Figure 5, the plunger 11 is provided with a reduced lower end portion so as to leave an annular space as at 18 between such reduced end portion of the 80 plunger 11 and the inner surface of the tappet body 9. Extending transversely through the wall of the tappet body 9 at suitable uniformly spaced points are a plurality of openings 19 which communicate at their outer ends with the annular groove 17 and at their inner ends with the annular space 18 between the reduced end of the plunger 11 and the tappet body 9. The openings 19 provide constant communication between the groove 90 17 and the space 18 because the reduced end portion of plunger 11 is of sufficient length to extend above the openings 19 even when the tappet is completely compressed or collapsed with the plunger 11 completely within the tappet body 9. Disposed within and seated upon the bottom or lower end wall of the tappet body 9 is a resilient block or rubber cushion 20 adapted to be engaged by the lower end of the plunger 11 when the tappet 100 shortens for absorbing shock.

Extending through the cushion 20 and the lower end of the tappet body 9 is an oil passage or opening 21 arranged to lead oil from the lower end of the tappet body 9 onto the 105 bearing surface or edge of cam 7.

In operation, the engine is started in the usual way so as to cause rotation of cam shaft 7 and the cam 7 carried thereby, at which time oil is supplied under pressure through the line 16 into groove 17 and through openings 19 into the annular space 18, the oil ultimately finding its way from the space 18 to a point between the cushion 20 and the lower end of plunger 11. Prior to starting the engine the screw 12 may be adjusted so as to leave a slight clearance space between the head of the same and the lower end of the rod or stem 8 in the usual way when the plunger 12 is substantially engaged at its lower end with the cushion 20. However, as soon as the oil under pressure finds its way between the cushion 20 and the lower end of plunger 11, the latter will be raised so as to close said clearance space and engage the head of screw or bolt 12 with the lower end of rod or stem 8. As the cam 7 turns with the shoe or plate 10 riding on the base circle of said cam, the tappet will be constantly engaged with the cam and the rod or stem 8, and oil will find its way 120 125 130

through opening or passage 21 onto the surface of the cam for minimizing wear. Upon continued rotation of cam 7 the projection of the latter will ride into engagement with the shoe or plate 10 and thereby effect lifting of the tappet and consequently cause lifting of rod or stem 8 for opening the associated valve, not shown. When this lifting action of the cam is had the opening 21 is less securely closed by the cam surface, and the liquid pressure of the liquid cushion between the plunger and the tappet body is partially relieved by a more pronounced flow of the oil through the passage 21 onto the cam 7. This 10 provides a film of oil on the cam surface so as to more thoroughly lubricate at a time when lubrication is more needed, and such film of oil will also serve to present a cushion-like medium between the contacting surfaces of the tappet body and the cam. At this time, the cam 7 will be starting upon its retreating period of movement for allowing the tappet and the push rod or stem to lower. This lowering action is effected and accelerated by the 20 closing spring of the valve which tends to force the plunger 11 downwardly into the valve body 9 as allowed by the relief of pressure through the opening 21. Consequently, the tappet will automatically shorten during its lowering movement for insuring permission of complete closing of the valve of the engine. As soon as the tappet completely lowers it will have been shortened to its extreme extent, at which time the lower end of 30 the plunger 11 will contact the cushion 20 so that any likely shock is absorbed. The parts are then disposed for a new cycle of operation as described above.

It will be noted that a liquid cushion is provided between the members 9 and 11 when the oil is contained in the annular space 18 even though the tappet is in completely shortened form, and such cushion is materially increased when the tappet is extended with the oil between the cushion 20 and the lower end 45 of plunger 11.

Naturally, considerable of the oil fed to the groove 17 will find its way between the contacting surfaces of the guide 5 and the tappet body 9 so that lubrication is had at this point for preventing wear of these parts.

The plunger 11^a may be substituted for the plunger 11 of Figure 5 in valve operating mechanism wherein the elements 12 and 13 are not employed. In such instances, the plunger is not interiorly threaded and the push rod or valve stem 8^a constitutes the valve lifting member and is extended into the plunger so as to directly contact with the lower end of the latter.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:—

1. A self-adjusting tappet for push rod 70 operating mechanisms, including a pair of telescopically and slidably associated members, means to supply oil under pressure between said tappet members for providing a liquid cushion therebetween and lengthening 75 the tappet for maintaining constant contact of the tappet with the cam and the push rod, said tappet having a longitudinal opening through the lower end thereof to allow the oil to flow from between the tappet members 80 to a point between the tappet and the cam and to partially relieve the liquid pressure of the cushion during the retreating movement of the cam whereby the tappet is allowed to shorten for permitting complete return movement of the push rod. 85

2. A tappet device for push rod operating mechanisms, wherein the tappet is interposed between an operating cam and the push rod, including a pair of telescopically and slidably associated members, means to constantly supply liquid under pressure between said tappet members to provide a liquid cushion therebetween, whereby the tappet is lengthened for maintaining constant contact of the tappet with the cam and the push rod, means to automatically partially relieve the liquid pressure of the cushion during the retreating movement of the cam, whereby the tappet is allowed to automatically shorten for permitting complete return movement of the push rod, and an elastic cushion interposed between the tappet members for absorbing shock incident to sudden shortening of the tappet. 100

3. A self adjusting tappet for a push rod operating mechanism, comprising a pair of telescopically and slidably associated tappet members, means to supply oil under pressure between said tappet members for providing a liquid cushion therebetween for lengthening the tappet to maintain constant contact of the tappet with the cam and push rod, said tappet having a longitudinal opening through the lower end thereof to allow the oil to flow from between the tappet members to a point between the tappet and the cam and to partially relieve the liquid pressure of the cushion during the retreating movement of the cam whereby the tappet is allowed to shorten to permit complete return movement of the push rod, one of said tappet members comprising a centrally bored body having a cylindrical exterior bearing surface in the lower end of which said longitudinal opening is formed, and the other tappet member comprising a plunger slidably fitted in the tappet body and having a closed lower end. 110 115

4. In combination, a guide, a tappet vertically slidable in said guide and comprising 120 125 130

a pair of telescopically and slidably associated members, a lifting cam engaged with the lower end of the outer one of the tappet members, arranged to be engaged by the upper end of the inner one of said tappet members, and means for continuously supplying oil under pressure between said tappet members to provide a liquid cushion therebetween and to lengthen the tappet for maintaining engagement of the tappet members with the cam and the valve lifting member and for simultaneously supplying the oil between the cooperating surfaces of the guide and the tappet and the cooperating surfaces of the cam and the tappet, said oil supplying means between the connecting surfaces of the tappet and the cam constituting means for relieving the pressure of the liquid cushion between the tappet members upon retreating movement of the cam and the lowering of the tappet and valve lifting member.

5. In combination, a guide, a tappet vertically slideable in said guide and comprising a pair of telescopically and slidably associated members, a lifting cam engaged with the lower end of the outer one of the tappet members, a valve lifting member arranged to be engaged by the upper end of the inner one of said tappet members, and means for continually supplying oil under pressure between said tappet members to provide a liquid cushion therebetween to lengthen the tappet for maintaining engagement of the members with the cam and valve lifting member and 35 for simultaneously supplying the oil between the cooperating surfaces of the guide and the

tappet and the cooperating surfaces of the cam and the tappet, said oil supplying means comprising an oil pressure line communicating with the bearing opening of the tappet guide, said outer tappet member being provided with an external annular groove and said inner member being reduced at the lower end, the tappet member having the external annular groove having transverse 45 apertures placing the groove in communication with the space provided between the tappet members by the reduced end of the other member whereby constant communication is had between the oil pressure line 50 and the space between the tappet members.

6. A tappet device for push rod operating mechanism, wherein the tappet is interposed between an operating cam and the push rod, comprising a pair of telescopically associated members, a bearing guide designed to receive said members, one of said members being designed to rest upon an operating cam and the other being designed for connection with the push rod, and means for forcing a liquid under pressure between the inner end of the inner one of said members and the outer member to lengthen the tappet to maintain constant contact between the same and the cam and push rod, and means for relieving the pressure through that surface of the tappet member against which said cam bears, at certain periods during the rotation of the cam.

In testimony whereof I affix my signature.

WILLIAM A. SEAMAN.
